CLOTH CLAMP

David Sigmond, Brooklyn, N. Y.

Application July 2, 1938, Serial No. 217,229

8 Claims. (Cl. 270—31)

This invention relates to tailoring equipment and the like, and more particularly to a device for clamping and pulling a length of fabric over the cutter's table and engaging it thereon to facilitate the measuring off of a plurality of equal lengths of material, and holding these lengths in superimposed relationship so that a plurality of cloth patterns may be cut simultaneously from the stack of material.

10 In garment manufacturing and tailoring establishments considerable difficulty is encountered by the cutters in arranging the material on the cutter's table. Usually the fabric is pulled by hand from a roller mounted at one end of the cutter's table and impaled on a row of nails at the other end. The desired length is then cut from the roller and placed on the table. This operation is repeated until the required number of superimposed layers of material has been cut. 20 This method, however, is utterly undesirable for the reason that the pull on the fabric exerted by hand is not uniform and therefore causes distortion of the warp and weft threads and unequal stretch of the superimposed layers. Consequently the patterns cut therefrom will not be entirely regular.

Furthermore considerable time is consumed in placing the layers edge to edge on the tables, which is necessary in order to reduce waste of 30 material and to insure regular cutting.

It is therefore the object of the present invention to provide a fabric pulling and holding device which will exert a uniform pulling action on the fabric, and subject the successive lengths 35 to an equal tension.

Another object of the invention is to provide a device of the character indicated which will facilitate the fastening of the layers to the table, and simultaneously release them from the 40 pulling mechanism.

Still another object is to provide a device which will insure equal measuring of lengths of fabric and regular cutting.

Other objects and advantages inherent in the 45 invention will become apparent as the specification proceeds, and when considered in conjunction with the accompanying drawings showing a preferred embodiment together with a possible modification.

In the drawings:

Figure 1 is a perspective view of a cloth clamp and pulling device according to the invention;

Figure 2 is a section along the line 2—2 of

55 Figure 1;

Figure 3 is a section along the line 3—3 of Figure 1;

Figure 4 is a rear view of the device shown in Figure 1;

Figure 5 is a fragmentary view of the end of 5 the cloth clamp in closed position;

Figure 6 is a view in perspective of the measuring device to which the cloth is attached;

Figure 7 is a section along the line 7—7 of 10 Figure 6;

Figure 8 is a perspective view of the cutting table showing the device according to the invention in operation;

Figure 9 is a perspective view of a modification;

Figure 10 is a section along the line 10—10 of 15 Figure 9;

Figure 11 is a fragmentary enlarged view of the cloth clamp shown in Figure 9;

Figure 12 is a section taken along the line 20 12—12 of Figure 9;

Figure 13 is a section similar to Figure 12, showing the clamp in closed position; and

Figure 14 is a section along the line 14—14 of 25 Figure 9.

Throughout the drawings the same reference characters serve to indicate the same or analogous parts.

Referring to Figure 8, the reference character 20 represents the cutting table upon which the cloth clamp generally indicated at 21 is operated. 30 The cloth clamp engages the edge of a length of fabric 22 which is supplied from a roller 23. The roller 23 as well as the reserve roller 24 are rotatably mounted in brackets 25 attached to the table 20. The table may be provided with 35 legs 26.

The measuring and attachment mechanism is generally indicated at 27 and is mounted adjacent one edge of the table 20. Although it is shown bolted to the table, it will be understood that 40 the mechanism may also be adjustably connected thereto without departing from the spirit of the invention.

Referring to Figures 1 to 6 inclusive, the cloth clamp comprises a pair of clamping members 45 28 and 29, which are hinged together along one edge by means of leaf springs 30. The latter tend to maintain the members 28 and 29 in open position.

The slat 31 is resiliently mounted on the clamp- 50 ing member 29 and normally raised thereover by means of the spring 32 and the slotted guide brackets 33. The springs 32 rest in pockets 34 on the clamping member 29 and terminate in a sharp point or spike 35, which extend through 55

apertures 36 in the slat 31. It will be noted that the apertures 36 are sufficiently large in diameter to afford the point 35 a certain amount of play.

The clamping member 29 is also provided with 5 a row of nails or spikes 37 along the free edge thereof, which extend through corresponding apertures 38 in the slat 31 and in the clamping member 28. The member 28 is also provided with apertures 39 for accommodating the points 10 or spikes 35 when the clamping members are in closed position.

The clamping member 28 is provided with a recess 40 for accommodating the slat 31 when the device is in closed position.

15 The closing operation is effected by bringing together the handles 41 and 42 mounted to the clamping members 28 and 29 respectively. The handles are held together by means of the hook or latch 43. The latter is provided with an outwardly bent spring 44 which engages the edge of the cutting table 20 and the purpose of which will be hereinafter explained.

The cloth clamp is pulled along the table on 25 casters 45 which are mounted in springs 46, and which in turn are attached to the clamping member 29. These springs permit the clamp to be pressed down toward the table top.

30 The guide member 47 normally engages the edge of the cutting table when the clamp is drawn along the same so that the edge of each successive length will lie parallel to the edge of the table.

The hinged edge of the member 29 is provided with a horizontal handle 48 for pulling the cloth clamp along the table, and a vertical handle 49 35 for pressing it downward towards the top of the cutting table.

40 The clamping members 28 and 29 as well as the slat 31 are provided with a series of corresponding notches 50, the purpose of which will hereinafter be described.

45 The rear edge of the clamping member 29 is also provided with a pair of notched brackets 51 which engage the stanchions 52 of the attaching device when the clamp has been pulled the distance corresponding to the length of the cloth to be cut. The stanchions 52 are reciprocable horizontally in the slots 53 of the board 54 against the tension of the spring 55 which is anchored at the forward end by means of a pin or bolt 56.

60 The board 54 is also provided with a row of nails or spikes 57 for engaging the cloth after it has been released from the clamp.

55 The operation of the device is as follows: The length of cloth 22 is impaled upon the spikes 35 whereupon the clamp is closed by pressing together the two handles 41 and 42. This closing operation will cause the spikes 37 to be projected through the apertures 38 of the slat 31 to impale the fabric and clamp it firmly between clamping 60 members 28 and 29 as the spikes penetrate into the corresponding apertures of the member 28.

65 The cloth clamp is then pulled along the cutter's table by the handle 48 until the stanchions 52 engage the slots of the brackets 51. In this position the spikes 57 will be directly beneath the notches 50. The fabric is impaled upon these spikes by pressing down the clamp by the handle 49. As the clamp is pressed down, the tension of the curved spring 44 engaging the lateral edge 70 of the cutter's table will gradually increase until it disengages the latch 43 from the handle 42, which in turn will cause the clamp to snap open. The released tension will cause the slat 31 to lift the fabric off the spikes 37, but it still will be impaled upon the points 35. It will be understood

that the spikes 57 are of sufficient length to extend above these points through the notches 50.

The fabric is released from the clamp by pulling the latter a distance further against the tension of the spring 55 until the spikes 57 are disengaged from the notches 50. Because of the play between the points 35 and the apertures 36, the former will tilt forward as the clamp is pulled back against the stanchions 52 and the cloth will slip off. The pressure on the handle 49 is then released and the clamp will spring back to its normal position, so that it can be returned for engagement with another length of cloth.

15 In the modification shown in Figures 9 to 14 inclusive, the slat 60 is resiliently mounted on the 15 clamping member 61 by means of springs 62 and slotted guide brackets 63. Instead of being attached to the end of the clamping member as in the embodiment shown in Figure 1, the guide brackets 63 are mounted in slots 64 on the clamping member 61 in order to make room for the locking mechanism which will hereinafter be described. The springs 62 rest in pockets 65 on the clamping member 61 and abut against the lower surface of the slat 60 to hold the latter normally 20 raised above the surface of the clamping member.

25 The points 35 of the preferred embodiment have been substituted for pointed spring fingers 66 which are rotatably mounted on a shaft 67 disposed in recesses 68 on the clamping member 61 30 and held normally upright by the spring 69. The slat 60 is provided with notches 70 to accommodate these spring fingers.

35 The leaf springs 36 have also been substituted by spring hinges 71 which will permit a greater degree of play between the clamping members 61 and 72. The clamping member 72 is recessed in a similar manner to the device shown in Figure 1 to accommodate the slat 60 when the clamp is in closed position. The notches 73 on the clamping member 72 serve to accommodate the spring fingers 66. The clamping members 61 and 72 as well as the slat 60 are also provided with notches 74 to accommodate the spikes 57 of the attachment device.

40 The clamping members 61 and 72 are locked together by means of the trigger 76 which is pivoted in the slot 77 on the clamping member 72. The trigger 72 may be pushed backwardly against the tension of the spring 78 which is mounted on 50 the lever arm 79 and bears against the lower surface of the clamping member 72.

45 The clamping member 61 is also provided with a recess 80 having a slot 81 for accommodating the trigger mechanism. When the clamping members are pressed together the curved end of the trigger will ride on the forward edge of the slot 81 and be pushed backward against the tension of the spring 78 until it snaps into locking position as shown in Figure 13.

55 A piston 82 is resiliently mounted in the recess 80 by means of the spring 83 interposed between the bushing 84 and the collar 85. The screw threaded bushing 84 is then held in position by the screw threaded cap 85 which clamps the disc 86 firmly against the floor of the recess 80. The piston 82 terminates at its upper end with a disc 87, normally resting on the disc 86, and at its lower end in a rubber ball 88 or similar article.

70 When the cloth clamp is pressed down to impale the fabric on the spikes 57, the ball 88 will engage the table and the disc 87 will engage the lever arm 79 to disengage the trigger 76 and the clamping members will snap open.

- The guide member 89 in this modification is provided with a ball bearing roller 90 which will reduce the friction and make the sliding engagement with the edge of the table smoother.
- 5 In other respects the modification shown in Figures 9 to 14 is identical with the preferred embodiment and the same parts have been given the same reference characters. It will be understood that the mode of operation is the same.
- 10 It will thus be noted that an improved cloth holding and measuring device has been provided, whereby the successive layers may be superimposed upon one another in accurate aligned relationship. The equal pull along the severed edge of the fabric will eliminate distortion and insure regularly cut patterns. Furthermore, the fabric is impaled directly upon the nails or spikes on the cutter's table by the novel cloth clamp so that manual handling is unnecessary.
- 15 20 It will also be apparent that many changes may be made and numerous details of construction may be varied through a wide range without departing from the principles of the invention as defined by the appended claims.
- 25 The following is claimed:
1. A device for attaching lengths of cloth and the like from a supply roller to a cutter's table having a transverse row of spikes for impaling the cloth, comprising a pair of clamping members for engaging the severed edge of the cloth and pulling it longitudinally of the table, compressible means on said clamping members for impaling the cloth on said spikes, and means controlled by the impaling operation for releasing the cloth from said clamping members.
  2. A device for attaching lengths of cloth and the like from a supply roller to a cutter's table having a transverse row of spikes for impaling the cloth, comprising a pair of resiliently hinged clamping members for engaging the severed edge of the cloth and pulling it longitudinally of the table, means for locking said clamping members in clamping position, said clamping members being notched to accommodate said spikes, resilient means on one of said clamping members for enabling manual impaling of the fabric on said spikes, and means controlled by the impaling operation for unlocking said clamping members to release the cloth.
  3. A device for attaching lengths of cloth and the like from a supply roller to a cutter's table having a transverse row of spikes for impaling the cloth, comprising a pair of resiliently hinged clamping members, for holding the severed edge of the cloth and pull it longitudinally of the table, flexible engaging means on one of said members for the cloth, a row of spikes along the free edge of one of said clamping members for impaling the fabric when said clamping members are in closed position, means for locking said members in clamping position, said clamping members being notched to accommodate the spikes on the cutter's table, resilient means enabling manual depression of said clamping members to impale the cloth on said last mentioned spikes, means controlled by the impaling operation for unlocking said clamping members, and resilient means between said clamping members for freeing the cloth from the spikes on one of said members.
  4. A device for attaching lengths of cloths and the like from a supply roller to a cutter's table having a transverse row of spikes on which the cloth is to be impaled, comprising a pair of resiliently hinged clamping members for holding and pulling the severed edge longitudinally of the table, flexible means on one of said members for engaging the cloth, gripping means along the free edge of said members for holding the cloth, means for locking said clamping members, means on said clamping members for enabling manual impaling of the fabric on said spikes, means controlled by the impaling operation for unlocking said clamping members, and compressible means between said clamping members for releasing the cloth from said gripping means.
  5. A device for attaching lengths of cloth and the like from a supply roller to a cutter's table having a transverse row of spikes on which the cloth is to be impaled comprising a pair of resiliently hinged clamping members for holding the severed edge of the cloth and pulling it longitudinally of the table, gripping means along the free edge of said members, a shield resiliently mounted between said members covering said gripping members when said members are in open position, and apertured to receive said gripping means when said members are closed, flexible engaging means for the cloth extending through said shield, locking means for holding said clamping members in closed position, a flexible carriage for said clamping members enabling manual depression thereof to impale the fabric on said spikes, notches on said members for accommodating said spikes, and means controlled by the impaling operation for unlocking said clamping members, whereby said shield will disengage the cloth from said gripping members.
  6. A device for attaching lengths of cloth and the like from a supply roller to a cutter's table having a transverse row of spikes on which the cloth is to be impaled, comprising a pair of resiliently hinged clamping members for holding the severed edge of the cloth and pulling it longitudinally of the table, a row of impaling members along the free edge of one of said clamping members, means between said clamping members and controlled by the closing operation for impaling the cloth on said impaling members, locking means for holding said clamping members in closed position, means on said clamping members enabling manual impaling of the cloth directly therefrom onto said spikes, means controlled by the impaling operation for unlocking said clamping members, and means for disengaging the cloth from said impaling members.
  7. A device for attaching lengths of cloth and the like to a cutter's table having a transverse row of spikes on which the cloth is to be impaled, comprising a pair of resiliently hinged clamping members for holding the severed edge of the fabric and pulling it longitudinally of the table, a row of impaling members along the free edge of one of said clamping members, means between said clamping members and controlled by the closing operation for impaling the fabric on said impaling members, a resiliently pivotable latch member having a lever arm on one of said clamping members, a recess having a slot for accommodating said latch member on said other clamping member to lock said clamping members together, a resiliently reciprocable rod depending from said recess, and adapted to engage said lever arm and the surface of the cutting table, a flexible carriage for said clamping members enabling manual depression thereof to impale the cloth on said spikes, said clamping members being notched to accommodate said spikes, whereby said rod will be pushed upward into said recess during the impaling operation to re-

lease said latch member, and means for disengaging the cloth from said impaling members.

8. A device for attaching lengths of cloth and the like from a supply roller to a cutter's table having a transverse row of spikes on which the cloth is to be impaled comprising a pair of resiliently hinged clamping members for holding the severed edge of the cloth and pulling it longitudinally of the table, gripping means along the free edge of said members, a shield resiliently mounted between said members covering said gripping members when said members are in open position, and apertured to receive said gripping means when said members are closed, flexible engaging means for the cloth extending through said shield, a resiliently pivotable latch

member having a lever arm on one of said clamping members, a recess having a slot for accommodating said latch member on said other clamping member to lock said clamping members together, a resiliently reciprocable rod depending from said recess, and adapted to engage said lever arm and the surface of the cutting table, a flexible carriage for said clamping members enabling manual depression thereof to impale the cloth on said spikes, said clamping members being notched to accommodate said spikes, whereby said rod will be pushed upward into said recess during the impaling operation to release said latch member, and whereby said shield will disengage the cloth from said gripping means.

DAVID SIGMOND. 15
